UNITED STATES PATENT OFFICE

ISIDOR DINSTMAN, OF NEW YORK, N. Y., ASSIGNOR TO YORKE SPECIALTY CORPORATION,
OF NEW YORK, N. Y., A CORPORATION OF NEW YORK

DESIGN FOR A CLOCK CASE

Application filed October 23, 1931. Serial No. 41,504. Term of patent 7 years.

To all whom it may concern:

Be it known that I, ISIDOR DINSTMAN, a citizen of the United States, and a resident of the city of New York, county of Bronx, and State of New York, have invented a new, original, and ornamental Design for a Clock Case, of which the following is a specification, reference being had to the accompanying drawings forming a part thereof, wherein—

Fig. 1 is a front elevational view of the clock case showing my new design and showing a clock dial through the front window of the clock case;

Fig. 2 is a side elevational view thereof; and

Fig. 3 is a top plan view thereof.

The parts of the drawing shown in white with dark shading are made of metal having a dull or bright finish, and the parts shown in black with light shading are made of a molded composition material such as "Catalin" which may also have either a dull or high polish finish. The parts made of the molded composition material may be of any color or of a combination of colors to provide one or more tone effects. The parts made of metal may be chromium plated in one or a combination of colors to provide one or more tone effects.

I claim:

The ornamental design for a clock case as shown and described.

ISIDOR DINSTMAN.
